UNITED STATES PATENT OFFICE

HEINRICH KÜCHENMEISTER, OF BERLIN, GERMANY

APPARATUS FOR MAKING SOUND RECORDS

Application filed December 15, 1927, Serial No. 240,327, and in Germany December 15, 1926.

My invention relates to apparatus for making sound records, and it is an object of my invention to provide an apparatus of this type in which the influence of the natural vibrations of the controlling means for the recording part is eliminated.

To this end I provide a single sound recording element in combination with any number of sound receivers. To each receiver I allot a controlling unit, and intermediate each controlling unit and the single recording element I provide means for independently, simultaneously and directly influencing the single recording element.

Records of any kind may be made with my improved apparatus, as record plates, films, magnetic strips, magnetic wires, etc., and any kind of receiver may be provided, as the usual horns, microphones, cathode-phones, etc.

Apparatus in which impulses from several receivers having, if desired, independent amplifiers and regulators, are transmitted to a common device for recording all impulses through the medium of a single electromagnet, have already been proposed. This type of apparatus involves the drawback that the electromagnet and the diaphragm with which it cooperates, possesses a natural vibration and therefore render more distinctly sounds in the vicinity of their resonance pitch. Such apparatus are not in any way an improvement over the old apparatus having but a single receiver.

In my invention, on the other hand, not less than two controlling units each receiving impulses from a separate receiver or receivers, act on the recording part which is provided with means for making impressions on the record.

I may also connect any of the controlling units in parallel or in series, or make some of them larger or smaller than the rest, so as to differentiate their influence on the recording part.

Natural vibration of the recording part may be eliminated by preferably frictionless, damping means.

With my improved apparatus, I am able to record separately the effect of a group of

instruments, as the violins, the flutes, etc., of a band playing.

In the drawings, an apparatus for mechanical and photographic recording are illustrated diagrammatically by way of example in Figs. 1 and 2, respectively.

Referring first to Fig. 1, *a* is a stylus on the recording element here shown as a disc *b* on a shaft *c*, *d'*, *d''*, *d'''* are armatures on the disc *b* which are acted on by electromagnet cores *e'*, *e''*, *e'''*, respectively. The armatures may be constructed as bands under tension, not shown, which in their normal position tend to hold the disc *b* in its neutral position.

The electromagnets *e'* . . . are the controlling units and the coil of each is connected with a set of binding posts *f'*, *f''*, and *f'''* which in turn are connected with sound receivers, not shown, and their amplifiers, if any.

g', *g''* are strong electromagnets which are connected to a battery or the like at *f* and equipped with cores which surround the disc *b*. They serve for damping the vibrations of the disc *b* which may be of aluminum and prevent independent vibration of the disc. Their action may be regulated by resistances, not shown, in their circuits.

The variations of current in the electromagnets *e'* . . . which are brought about by the sound receivers, cause the disc *b* to rock about its axis as the attraction is increased or reduced, and corresponding movement is imparted to the stylus *a*. When the disc is moving in the magnetic fields of the magnets *g'*, *g''* eddy currents set up in the disc *b* which damp its movements and prevent rocking of the disc when the current impulses in the controlling units have ceased.

The coils of the electromagnets *e'* . . . are exchangeable in order to adapt them to the character of the sounds to be recorded as to their resonance. As the resonance properties of the electromagnets are different, accentuation of a given resonance by the apparatus is prevented, the more so as natural vibrations are damped out by the magnets *g'*, *g''*.

Preferably, the axis about which the disc *b* is rocking is in its centre of gravity, and means, not shown, such as springs, are provided for holding the disc in its neutral position.

5 Referring now to Fig. 2, the units *e*'₁, *e*'₂, *e*'₃ are pairs of electromagnets which control a mirror *a'* in the loop of an oscillograph *k*. A ray of light is projected on 10 the mirror *a'* from a lamp *p'* and a system of lenses *q*, and reflected on a sensitized film *t* through a lens *r*. The film is moving on a roller *s* and is imprinted with a curve *u* by the spot of light from the mirror *a'* 15 and the lens *r* which when the film is developed, appears as a dark line.

The controlling units are independent as in the previous example, and are connected with separate sound receivers *l'*, *l*², *l*³ and 20 with amplifiers *m'*, *m*², *m*³.

The action of the electromagnet pairs *e*'₁, *e*'₂ and *e*'₃ in the loop *k* varies under the influence of the current variations effected by the three microphones or sound receivers 25 *l'*, *l*² and *l*³, and magnified by the amplifiers *m'*, *m*² and *m*³, and the mirror *a'* rocks in proportion to the variations of the sound received at the microphones. In consequence, the light issuing from the lamp *p'* and reflected onto the film *t* by the mirror *a'* will mark on the film a curve *u* which exactly corresponds to the variations of current and, therefore, to those of the sound impulses received. The curve *u* may be translated into sound by any suitable means.

Each electromagnet in the three pairs may be exchanged independently of the others so that it is possible to employ stronger or weaker electromagnets, as conditions may require.

40 The loop *k* may be provided with a device, indicated diagrammatically in Fig. 2 at *g'*, for damping the natural vibrations in a manner similar to that shown in Fig. 1.

45 I am not limited to any particular type of controlling units, as the units can be operated by static or electrostatic vibrators, pneumatic, or any other suitable means.

I claim:

50 1. An apparatus for making sound records comprising a movable recording element including a mirror and an oscillograph loop, a plurality of controlling units for said recording element, a sound receiver 55 connected with each unit, means for projecting light on said mirror, means for moving a sensitized film past said mirror in such a manner as to be struck by the light reflected by said mirror and means intermediate each controlling unit and said recording element for independently, simultaneously and directly influencing said single recording element.

60 2. An apparatus for making sound records comprising a single sound recording

element, a plurality of sound receivers, a controlling unit allotted to each receiver, and means intermediate each controlling unit and said recording element for independently, simultaneously and directly influencing said single recording element.

70 3. An apparatus for making sound records comprising a single sound recording element, a plurality of sound receivers, a controlling unit allotted to each receiver, an amplifier interposed between each receiver and its controlling unit, and means intermediate each controlling unit and said recording element for independently, simultaneously and directly influencing said single recording element.

75 4. An apparatus for making sound records comprising a single sound recording element, a plurality of sound receivers, a controlling unit allotted to each receiver, said units being connected in parallel, and means intermediate each controlling unit and said recording element for independently, simultaneously and directly influencing said single recording element.

80 5. An apparatus for making sound records comprising a single sound recording element, a plurality of sound receivers, a controlling unit allotted to each receiver, said units being of various sizes, and means intermediate said controlling unit and said recording element for independently, simultaneously and directly influencing said single recording element.

85 6. An apparatus for making sound records comprising a single sound recording element, means for moving a record past said recording element, a plurality of sound receivers, a controlling unit allotted to each receiver, and means intermediate each controlling unit and said recording element for independently, simultaneously and directly influencing said single recording element.

90 7. An apparatus for making sound records comprising a single sound recording element, means for damping the movements of said recording element, a plurality of sound receivers, a controlling unit allotted to each receiver, and means intermediate each controlling unit and said recording element for independently, simultaneously and directly influencing said single recording element.

95 In testimony whereof I affix my signature.

HEINRICH KÜCHENMEISTER.
